UNITED STATES PATENT OFFICE.

E. NORRIS SULLIVAN, OF BOSTON, MASSACHUSETTS.

SHOE-FASTENING.

SPECIFICATION forming part of Letters Patent No. 250,403, dated December 6, 1881.

Application filed April 23, 1881. (No model.)

To all whom it may concern:

Be it known that I, E. NORRIS SULLIVAN, of Boston, in the county of Suffolk and State of Massachusetts, have invented a new and 5 useful Improvement in Fastenings for Shoes, Gloves, and Corsets, of which the following is a specification.

The object of my invention is to produce a simple and efficient fastening for gloves, shoes, 10 corsets, &c.; and the invention consists in constructing the fastening of three pieces of thin metal, which can be struck out with a die, and by bending and connecting together the said pieces they will constitute a fastening without 15 the necessity of solder or riveting, with the exception of a pin which is riveted to one of the pieces.

Referring to the drawings, Figure 1 is a perspective view of a fastening as completed, 20 shown on a large scale. Fig. 2 is a side elevation of the same. Fig. 3 is a vertical section of Fig. 2 on the line $x-x$. Figs. 4, 5, and 6 represent the several parts of the fastening as struck out from sheet metal.

25 b is the base of the fastening, composed of a piece of metal struck out, as seen in Fig. 4. It has two ear-pieces provided with holes $f' f'$, and two slots, $g g$, and a hole, e' . The top a of the fastening is struck out in the form shown 30 in Fig. 5, having a circular enlarged head and two projections, ff , as shown.

Fig. 6 shows the piece used for securing the fastening to the glove, shoe, &c.

In putting the parts together to form the 35 fastening the two ear-pieces of the plate 1 , Fig. 4, are bent over inward, so that the holes $f' f'$ will constitute bearings for the projections ff on the plate 2 , Fig. 5, which is bent in the form shown in Figs. 1 and 2. Underneath the plate b is a short narrow strip of 40 steel or elastic metal, c , to the front end of which is secured a pin, e , which passes up through the hole e' in plate b . The strip or spring c extends back and serves to hold the 45 rear end of plate a in an open or closed posi-

tion, the end and rear bent portion of the plate a being caused to bear upon the spring c . The bent end of the plate a is prevented from opening too far by the bent-over ears $f' f'$. The upper piece, a , acts as a spring-hinge, and is held 50 closed upon the pin e by means of the spring c .

m represents the portion of the glove, shoe, &c., to which the fastening is attached. The attachment is effected by means of the piece 3, Fig. 6, the center of which may be circular, 55 as at d ; or the piece may consist of a straight strip. The part d is placed under the portion m of the glove, &c. The two ends $h h$ are bent up and passed through the holes gg of b , plate 1, and then turned down upon the same, as 60 shown in Figs. 1 and 3, so as to form a clasp.

In operation, the plate a is raised up, when an eyelet or hole in the opposite part of the shoe, glove, &c., to be fastened is placed upon the pin e , and the plate a is shut down, thus 65 securely holding the parts together.

The pin e may have a slight inclination inward, if desirable, in order to prevent the liability of the eyelet slipping off the pin.

In Fig. 4 an extension, i , is shown, which 70 may be bent under the base b and serve the purpose of a separate spring.

What I claim as my invention is—

1. A fastening for gloves, shoes, &c., composed of the plate a , provided with the projections ff , the plate b , provided with two ear-pieces, and the metal strip c , substantially as and for the purpose set forth. 75

2. The plate b , provided with the ears f' , in combination with the plate a , provided with 80 the projections f , connected and operating together as described and shown.

In testimony whereof I have signed my name to this specification in the presence of two subscribing witnesses.

E. NORRIS SULLIVAN.
